(57) **CLAIM**

The ornamental design for a vacuum shaver, as shown and described.

DESCRIPTION

FIG. 1 is a top, left, front perspective view of a vacuum shaver showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is another top, left, front perspective view of a vacuum shaver in another condition of use;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The broken lines in the figures illustrate portions of the vacuum shaver which form no part of the claimed design. The additional broken lines showing the comb of the Vacuum Shaver are to show environment and form no part of the claimed design.

1 Claim, 14 Drawing Sheets
